(57) **CLAIM**

The ornamental design for a wall bracket, as shown and described.

DESCRIPTION

FIG. 1 is a front perspective view of a wall bracket, according to my new design;

FIG. 2 is a front view thereof;

FIG. 3 is a first side view thereof;

FIG. 4 is a rear view thereof;

FIG. 5 is a second side view thereof;

FIG. 6 is a top view thereof;

FIG. 7 is a bottom view thereof;

FIG. 8 is a rear right perspective view thereof; and,

FIG. 9 is a rear left perspective view thereof.

In FIGS. 1, 2, 4, and 6-9, the wall bracket is shown with pairs of symbolic, jagged break lines between right and left side portions of the wall bracket. The appearance of any length of the wall bracket between the break lines forms no part of the claimed design.
